UNITED STATES PATENT OFFICE.

ALFRED G. SCHOETTEL, OF BROOKLYN, NEW YORK, ASSIGNOR TO AMERICAN CAN COMPANY, OF NEW YORK, N. Y., A CORPORATION OF NEW JERSEY.

MEANS FOR SECURING SLIP-COVERS UPON CANS AND CONTAINERS.

1,279,018.

Specification of Letters Patent. Patented Sept. 17, 1918.

Application filed December 22, 1913. Serial No. 808,086.

To all whom it may concern:

Be it known that I, ALFRED G. SCHOETTEL, a citizen of the United States, residing in Brooklyn, in the county of Kings and State 5 of New York, have invented a new and useful Improvement in Means for Securing Slip-Covers Upon Cans and Containers, of which the following is a specification.

This invention relates to a means for securing slip covers upon cans and containers. 10 And the invention consists in providing the slip cover with an outwardly projecting bead and the container body with an inwardly projecting bead, the two beads being alined 15 together when the slip cover is in place and in further providing a flexible wire or key to be inserted in the cavity formed by the two grooves, thus locking the cover to the body while the key remains in place. 20 In the accompanying drawing which forms a part of this specification, Figure 1 is a side elevation of a can or container and its locked slip cover embodying this invention. Fig. 2, is a vertical central section of 25 the same. Fig. 3 is a horizontal section taken on the line 3—3 of Fig. 2.

In said drawing, A is a can or container. B is a slip cover for said container. a is an inwardly projecting circumferential bead or 30 groove in the body of the can near its upper or open end. b is a coincident outwardly projecting bead or groove in the slip cover which, when the slip cover is applied to the can, is positioned to come opposite to the 35 groove in the can body. C is a flexible key which may consist of a piece of annealed wire of a proper size to pass readily into the cavity formed by the oppositely turned and coincident beads or grooves in the container 40 and cover. c represents one end of this key or annealed wire bent at an angle to afford a hand hold for its more convenient manipulation in inserting and removing the key from its seat. D is an opening or portal cut 45 in the slip cover at the bead or groove so that when the slip cover is applied to the container the key may be readily inserted into the seat or removed therefrom for locking and unlocking the same. At Fig. 1, E 50 indicates a gummed small label or seal, shown in dotted lines, the same serving as a seal to cover and close the key aperture, to prevent removal of the key without break-

ing the seal. F is a shoulder on the container body, formed in this instance by necking in the open end of said body. This shoulder may serve to position the slip cover in applying said cover to the container to thus insure the bringing of the two parts of the key seat in alinement with each other 60 or this alinement may be obviously effected by the upper edge of the can body coming into contact with the cover.

In the instance illustrated both the container and its slip cover are made of sheet 65 metal but this is not essential to the invention as the container may obviously be made of hard fiber and the cover of sheet metal, or both container and slip cover may be made of fiber or paper and some of the results of my invention achieved thereby. 70 Although the key is shown to be circular in cross section to correspond to the seat or cavity having a circular cross section, it is obvious that the cross section of the key 75 may be that of a flat band or rectangle and the seat of corresponding shape. So too, in the instance illustrated, a cylindric container and slip cover are shown, but it is obvious that the invention is equally applicable to 80 other forms of container than cylindric, or even curvilinear. And while it is preferred to employ only a single key, it is quite obvious that more than one key may be used, and indeed in rectangular containers more 85 than a single key would be necessary.

This slip cover container is peculiarly adapted to proprietary goods where the dealer desires to securely close and even seal the package during transportation to 90 prevent loss of contents or fraudulent reuse of the package. Since this package when filled, closed, locked and sealed cannot accidentally open during transportation and handling, cannot be opened without destroying the seal, and when opened in the hands of the consumer by the removal of the key, becomes a container with a simple, easily handled slip cover that requires no tool or special manipulation for its opening and closing. This lockable, sealable 95 slip cover container possesses the following advantages. It is very cheap and easy to manufacture; it is secure against accidental removal or loosening of the cover 100 during transport; it may be securely sealed;

the lock may be easily opened; and finally in the hands of the consumer it may be treated as an ordinary slip cover can.

I claim:—

5. 1. A container of the character described, comprising in combination: a can body having an inturned annular bead; a cover having a downturned flange adapted to slip over the top of the can body and having an out-turned annular bead arranged to register with the bead on the can body to form a peripheral groove when the cover is in place, the out-turned bead being formed with an aperture; and a removable 10 peripheral locking member fitting in said groove and having an end adapted to be drawn through said aperture, the lower portion of the bead of the cover being inwardly extended and locked beneath the said locking member to secure the cover to the body, the locking member being adapted to be withdrawn endwise from said groove to allow the cover to be lifted from the can.
15. 2. A container of the character described, comprising in combination: a can body having a necked-in open end formed with an inturned annular bead; a cover having a downturned flange adapted to slip over the top of the can body and having an out-turned annular bead arranged to register with the bead on the can body to form a peripheral groove when the cover is in place, the out-turned bead being formed with an aperture; and a removable peripheral locking member fitting in said groove 20 and having an end adapted to be drawn through said aperture, the lower portion of the bead of the cover being inwardly extended and locked beneath the said locking member to secure the cover to the body, the locking member being adapted to be withdrawn endwise from said groove to allow the cover to be lifted from the can.
25. 3. A container having a body formed with an exterior circumferential bent-in groove, and a cover having a circumferential bent-out groove which is arranged to register oppositely with the said groove or the body when the container is closed by said cover, the said cover having an opening into its groove for the longitudinal and circumferential insertion of a peripheral and removable locking member.
30. 4. A container having a body formed with an exterior circumferential bent-in groove, and a cover having a circumferential bent-out groove which is arranged to register oppositely with the said groove or the body when the container is closed by said cover, the said cover having an opening into its groove for the longitudinal and circumferential insertion of a peripheral and removable locking member.
35. 5. A container having a body formed with an exterior circumferential bent-in groove, and a cover having a circumferential bent-out groove which is arranged to register oppositely with the said groove or the body when the container is closed by said cover, the said cover having an opening into its groove for the longitudinal and circumferential insertion of a peripheral and removable locking member.
40. 6. A container having a body formed with an exterior circumferential bent-in groove, and a cover having a circumferential bent-out groove which is arranged to register oppositely with the said groove or the body when the container is closed by said cover, the said cover having an opening into its groove for the longitudinal and circumferential insertion of a peripheral and removable locking member.

member being adapted to be withdrawn endwise from said groove to allow the cover to be lifted from the can.

3. A container of the character described, 45 comprising in combination: a can body having an inturned annular bead; a cover having a downturned flange adapted to slip over the top of the can body and having an out-turned annular bead arranged to register with the bead on the can body to form a peripheral groove when the cover is in place, the out-turned bead being formed with an aperture; and a removable peripheral locking member fitting in said 50 groove between the cover flange and the body and extending continuously around the can and having an end adapted to be drawn through said aperture, the lower portion of the bead of the cover being inwardly extended and locked beneath the said locking member to secure the cover to the body, the locking member being adapted to be withdrawn endwise from said groove to allow the cover to be lifted from the can. 65

4. A container having a body formed with an exterior circumferential bent-in groove, and a cover having a circumferential bent-out groove which is arranged to register oppositely with the said groove or the body when the container is closed by said cover, the said cover having an opening into its groove for the longitudinal and circumferential insertion of a peripheral and removable locking member.

Signed at New York, N. Y., this 17th day of December, 1913, in the presence of two subscribing witnesses.

ALFRED G. SCHOETTEL.
